UNITED STATES PATENT OFFICE.

GEORGE T. JOHNSON, OF COLUMBUS, OHIO, ASSIGNOR TO THE BUCKEYE STEEL CASTINGS COMPANY, OF COLUMBUS, OHIO.

CAR-TRUCK SIDE FRAME.

,084,278.

Specification of Letters Patent. Patented Jan. 13, 1914.

Application filed August 8, 1913. Serial No. 783,834.

to all whom it may concern:

Be it known that I, GEORGE T. JOHNSON, of Columbus, in the county of Franklin and State of Ohio, have invented certain new and useful Improvements in Car-Truck Side Frames; and I do hereby declare the following to be a full, clear, and exact description of the invention, such as will enable others skilled in the art to which it appertains to make and use the same.

My invention relates to car truck side frames, particularly adapted for freight cars where the service involves the carrying of heavy loads, and where strength and simplicity of construction as well as economy in manufacture is desired.

It is well known that in passing around curves or over rough tracks, the side movement of the cars or the lateral thrust, is, at times, considerable. It is also well known, that in using steel for parts which are subjected to considerable and intermittent stresses, the presentation of a surface of considerable width or size, to resistance of fiber stresses, is decidedly more effective than where an edge, or a comparatively small surface is provided for such purpose. Again in making castings, particularly of steel, where an edge or comparatively thin surface is provided for taking fiber stresses, a slight imperfection in the casting would more seriously impair the strength and serviceability of the outer fibers, than a greater imperfection would in a larger surface.

The object, therefore, of my invention is to provide a truck side frame adapted to have not only the necessary vertical strength but also have its metal so disposed as to withstand all lateral stresses to which the same may be subjected, and it consists in a cast metal side frame having its top, diagonal and upright members of channel section.

In the accompanying drawings, Figure 1 is a view in elevation of a truck side embodying my invention, and Figs. 2, 3, 4, 5 and 6 are views in section taken respectively on the lines A—B; C—D; E—F; G—H, and K—L of Fig. 1.

The frame consists of the top member 1, diagonal members 2, integral at their upper ends with member 1, and at their lower ends

with bottom member 4, and the vertical or upright members 3 integral at their upper ends with top member 1, and at their lower ends with the bottom and diagonal members 55 4 and 2. The two ends of the frame, at the juncture of the top and diagonal members, are provided with the extensions 5, which are designed to rest on the journal boxes, and through which the load that is imposed on 60 the truck frame, is supported on the wheels.

The top of the bottom member 4 forms a seat for the springs carrying the bolster and the inner flange of the top member, at the juncture of the latter with the two upright 65 members, is extended to form brake hanger brackets as shown in Fig. 1.

The members 1, 2, 3 and 4 of the frame, are of channel shape in cross-section, beaded as at 6 on the outer edges of the side 70 members or flanges of the channels, as clearly shown in Figs. 2, 3, 4, 5 and 6, so that in the event of lateral strains falling upon any of the members, a comparatively wide surface is presented to take care of the fiber 75 stresses.

The top of the bottom member 4 is closed as shown in Fig. 6 in order to form a seat 7 for the springs, which carry the bolster. The object of the beads 6 is to provide slight 80 lateral projection which stiffen the vertical surfaces of the channels laterally and avoids all sharp or comparatively thin edges, which would be liable, under ordinary stresses to 85 check or crack.

In this improved side frame, the outer edges of all the members are the floors or closed sides of the channels and the closed bottom together with sides of the channels present extensive surfaces or edges that minimize the impairment of a casting, in the event of a defect.

Having fully described my invention what I claim as new and desire to secure by Letters-Patent, is:—

1. A cast metal side frame having top, diagonal and upright members so located as to form a central opening and an opening at each side of the central opening, the said members being of channel section, the free 100 edges of the flanges of which, form the walls of the two side openings.

2. A cast metal side frame for car truck consisting of top, diagonal and upright members of channel section and bottom member of box section, the top member of
5 which at the juncture with the upright member being so constructed and flanges extended, so as to enable the brake hanger bracket to be cast integral with same.

In testimony whereof, I have signed this specification in the presence of two subscr- 10
ing witnesses.

GEORGE T. JOHNSON
